United States Patent Office.

PETER A. MOWERS, OF CLEVERSBURG, PENNSYLVANIA.

Letters Patent No. 85,752, dated January 12, 1869; antedated January 2, 1869.

IMPROVEMENT IN MORTISING-MACHINES.

The Schedule referred to in these Letters Patent and making part of the same.

To all whom it may concern:

Be it known that I, PETER A. MOWERS, of Cleversburg, in the county of Cumberland, and State of Pennsylvania, have invented a new and useful Improvement in Mortising-Machines; and I do hereby declare the following to be a full, clear, and exact description thereof, reference being had to the accompanying drawings, which are made a part of this specification.

The subject of my invention is a novel and simple machine, for mortising fence-posts, framing for buildings, &c., adapted to cut at different angles relatively to the frame, or be reversed; and also to be adjusted vertically and longitudinally in the frame, without impairing its movement.

In the drawings—

Figure 1 is a plan view of my improved machine, with a portion of the sliding frame broken away, to expose the parts beneath.

Figure 2 is a longitudinal section on the line *x-x*, fig. 1.

Figure 3 is a transverse section on the line *y-y*, fig. 1.

Figures 4 and 5 are enlarged detached views of a different form of cutter from that shown in the other figures, with a portion of its supporting-hanger and driving-shaft.

The frame of my machine may consist of a bed-piece, A, provided with a slot or aperture, *a*, for the passage of the cutter in cutting through the material, which is generally inserted transversely of it; four or more legs, A¹, side pieces or ways, A², having suitable grooves, *a*², in their inner edges, for the reception of corresponding tongues on the sliding frame, and end pieces or battens, A³ A⁴, which respectively form bearings for the operating- and adjusting-devices, and the latter of which is made removable by means of bolts, *a*⁴, or equivalent devices, to admit of the withdrawal of the sliding frame for any purpose.

B may represent the driving-wheel or pinion. It is mounted in bearings, *b* *b*', on the end piece A³ of the frame A and bracket C, and provided with a crank, D, crank-wheel, pulley, or other device, for imparting or transmitting motion to it.

E is a stud-shaft mounted in the bearing, *e*, on the lower edge of the bracket C, and provided with a pinion, F, which meshes with the driving-wheel B.

The shaft E is formed with a tubular portion, E', for the reception of the end of the shaft G, said tubular portion E' being further provided with longitudinal slots, *e*', for the reception of the ends of the pin *g*, which connects the movements of said shafts E and G, the elongated tubular portion and slots allowing the endwise movement of the shaft G in the longitudinal adjustment of its supporting-frame.

H represents a frame or table, provided with lateral ribs or tongues, *h*, which occupy the grooves *a*² in the side pieces A² of the frame A, in which it is thus adapted to be adjusted longitudinally by means of the

screw I, a nut, J, and tubular portion, *j*, being provided in the frame H for its reception.

The screw I is journalled in the bearing, *i*, in the end piece A⁴ of the frame A, is provided with a hand-wheel, I', by which to operate it, and is held from longitudinal displacement by the shoulders *i* *i*'.

K is an annular or perforated circular disk, mounted in a shouldered circular opening, H', in the surface of the table H, for the reception of the hanger of the cutter and its appurtenances, a similar disk, K', being mounted, at a suitable distance below the surface of the table, in an annular seat, L, which is supported from the lower side of the table H by brackets L¹ L² L³.

M represents a hanger, having a dovetailed or other angular shank, M¹, which occupies the correspondingly-formed grooves *m* in the disks K and K'.

Stud-shafts M² M³, and vertical bearings M⁴ M⁵, are provided on said hanger, at suitable points, for the reception, respectively, of the rotary cutter-head N, the cog-wheel O, and the vertical shaft P.

A fork, Q, pivoted at *q* to the bracket L¹, and forming at Q' a handle, by which to operate it, is employed to elevate the hanger M and its appurtenances, when desired, a grooved enlargement, *p*, being provided for the reception of said fork, when preferred.

The shaft G has its bearing in the hanger R, and carries a bevel-gear wheel, S, which meshes with the bevel-teeth *t* of the gear-wheel T, the straight teeth *t*' of which mesh with the sliding pinion U on the shaft P. The shaft P further carries a bevel-pinion, V, on its lower end, which meshes with the bevel-teeth *o* of the cog-wheel O.

The circumferential teeth *o*' of the wheel O are arranged to correspond with the teeth *n* of the cutter-head N, which teeth converge from side to side, to allow of the insertion of the alternate knives *n*¹ *n*¹' on opposite sides of its periphery, to adapt it to cut the entire width of the cutter-head.

W is a chip-guard, formed on or attached to the hanger M, in any suitable manner, to protect the gearing V *o*.

The annulus K is provided, on its periphery, with teeth or cogs, *k*, which are meshed by a pinion, X, for the purpose of turning the cutter-head, to cause it to cut at different angles relatively to the frame.

The pinion X is seated in the circular depression H² in the face of the table H, and has its bearing at the centre of a circular or segmental bracket, Y.

An arm, Z, is rigidly attached to the pivot of the pinion X, and is provided, at its outer end, with a clutch, *z*, operated by a hand-screw, *z*'. By loosening the screw *z*' the handle may be freely turned, and with it (through the gearing X *k*) the hanger M and its appurtenances, to any desired extent, and there locked by tightening the screw *z*'. This arrangement may, however, be dispensed with, and a simple spring-catch, provided with a suitable lug, to engage with the notches between the teeth of the disk K, be substituted therefor.

As shown in figs. 4 and 5, the gear-teeth of the cutter-head N may be formed in the side, and the motion imparted to it direct from the bevel-pinion V.

The knives n^1 , any desired number of which are used, are attached, by set-screws n^2 , in the apertures n^3 , and are arranged alternately on the opposite sides of the periphery of the head, as before described.

Having thus described my invention, the following is what I claim as new therein, and desire to secure by Letters Patent.

1. I claim the rotary cutter-head N, having its knives n^1 n^1 arranged alternately on the opposite edges of its periphery, substantially as and for the purpose specified.

2. The divided shaft G g, E' e', so constructed and arranged as to permit the sliding motion of the table H, without interfering with the rotation of the said shaft.

3. In combination with the sliding hanger M, having

an angular shank, M', I claim the circular perforated disks K K', constructed and arranged substantially as described, and adapted to be rotated to turn or reverse the cutter, in the manner and for the purpose specified.

4. I claim the rim or range of cogs n, arranged obliquely around the periphery of the cutter-head N, for the purpose of avoiding the knives, in combination with a correspondingly-oblique cog-wheel O o', for driving the same, substantially as described.

5. The chip-guard W, constructed and arranged as shown and described, to protect the gearing V o.

To the above specification of my invention I have signed my hand, this 30th day of April, A. D. 1868.

P. A. MOWERS.
